UNITED STATES PATENT OFFICE.

HARRY T. KRAKAU, OF CLEVELAND, OHIO, ASSIGNOR TO THE NATIONAL MALLEABLE CASTINGS COMPANY, OF CLEVELAND, OHIO, A CORPORATION OF OHIO.

DRAFT-GEAR.

1,052,668.

Specification of Letters Patent. Patented Feb. 11, 1913.

Application filed June 30, 1910. Serial No. 569,781.

To all whom it may concern:

Be it known that I, HARRY T. KRAKAU, a citizen of the United States, and a resident of Cleveland, Cuyahoga county, Ohio, have 5 invented a new and useful Improvement in Draft-Gears, of which the following is a full, clear, and exact description, reference being had to the accompanying drawings, forming part of this specification, in which—

10 Figure 1 is a view partly in plan and partly in horizontal section of a portion of a car under framing having my improved draft gear applied thereto; Fig. 2 is a longitudinal vertical section on the line II—II 15 of Fig. 1; Fig. 3 is a vertical section of a portion of the gear on a larger scale; Fig. 4 is a section on the lines IV—IV of Fig. 2; Fig. 5 is a section on the lines V—V of Fig. 3; and Fig. 6 is a detail view of one of the 20 parts, and hereinafter more fully described.

My invention has relation to draft gears, and is designed to provide a gear and buffer which will distribute the strains upon the buffer in a direct line and to the best advantage of the car and other material offering resistance.

A further object is to provide a construction so arranged as to absorb substantially all buffing stresses through the buffer only 30 and all pulling stresses through the coupler only.

Other objects and advantages of my invention will hereinafter appear.

The nature of the invention will be best 35 understood by reference to the accompanying drawings, in which I have shown the preferred embodiment thereof, and which will now be described, it being premised, However, that various changes can be made 40 in the details of construction and arrangement of the various parts by those skilled in the art without departing from the spirit and scope of my invention as defined in the appended claims.

45 In these drawings, the numeral 2 designates the center sills of the car, which, in order to enable the application of my invention, are caused to spread or diverge forwardly of the bolster so as to admit of proper lateral movement of the buffer.

50 3 is a buffer segment, which is, in this case, a casting which fits between and is rigidly secured to the diverging forward ends of the sills 2, and which is made strong enough 55 to receive all blows delivered to it. In order

to relieve the bolts or rivets by which this casting is secured to the sills, it is preferably formed with a lip 4 at each end, these lips abutting against the forward ends of the center sills. The casting is of segmental 60 form with curved front and rear edges, the center of their arcs being the center of movement of the radially swinging buffer hereinafter described.

5 designates a main buffer casting having 65 the transverse buffing head. This main buffer casting is of the split shank type, its split or forked shank 5^a embracing the buffer segment 3 in the manner clearly shown in Figs. 2 and 3.

7 is a radially swinging draft member 70 which is pivotally connected by a pin 8 with a pivot casting 9 which is rigidly secured between the straight portions of the center sills in the rear of their point of divergence 75 and which also acts as a bolster filler. The entire draft gear swings radially about the pin 8 as a center. The draft member is formed with a downwardly offset portion 7^a 80 at its forward end, which extends underneath the shank of the main buffer casting and also underneath the buffer segment, and which is constructed to form a case or pocket for the draft rigging. The rear portion of the draft member extends backwardly from the intermediate portion 7^a in a substantially horizontal direction and in alinement with the shank of the main buffer casting and with the pivot casting.

85 Interposed between the rear end of the buffer shank and the radially swinging draft member, are buffer springs 10 and 11. These are preferably in twin arrangement, each having one spring placed within the other, the inner one being an auxiliary 90 spring which normally keeps the buffer out in advance of the coupler, although not offering a heavy resistance, to thereby permit the couplers to couple easily and at the same time eliminate the possibility of a gap 95 between the buffers even though the coupler knuckles wear. Until the couplers are coupled, these auxiliary springs 10 offer the only resistance. Any further compression of the buffer, however, acts directly 100 against the heavy outside coils 11.

105 The draft rigging may be of any suitable character. In the form shown, it consists of two springs 12 and 13 arranged in tandem, the spring 12 being seated between a 110

front follower 14 and a center block or member 15; and the rear spring 13 being seated between said block and the rear follower 16. A transverse pin 17 passes loosely 5 through the block 15 and into the side walls of the draft rigging pocket or case, thereby permitting sufficient vertical movement of the draft rigging and coupler and providing means in a draft gear of this character, 10 which will permit vertical movement of the coupler head so that couplers when coupled together can be maintained in substantial alignment in a vertical plane, notwithstanding changes in the grade of the track which, 15 if the couplers were restrained from vertical movement by their attachments to the car, would cause them to angle with each other in a vertical plane, thereby resulting in disastrous strains to their parts or to the 20 car structure. 18 is a coupler, which is also of any suitable type; and which coupler is provided with bottom-operating mechanism 19. The shank of the coupler is rigidly secured to the yoke 20, which is placed with 25 in the draft rigging case or pocket, and which surrounds the followers and draft rigging springs in the usual manner. The forward spring 12 is interposed merely to keep the coupler out to its proper normal 30 distance. The rear draft spring is of sufficient capacity to receive and transmit all pulling strains.

The forward end of the draft gear is supported on the under side of the main buffer casting, this support, as shown in Figs. 3, 35 4 and 5, being formed in part by depending lugs 23^a on the main buffer casting, and in part by a buffer shank filler. This filler comprises two castings 21, which slide into 40 the buffer shank from opposite sides, and are secured by through-bolts 21^a. These two sections of the filler have depending inwardly projecting jaws with horizontal faces 22, which engage corresponding bearing faces on the under side of lateral flanges or projections 23 on the draft gear case 45 or pocket. These filler castings act as spacers for the prongs of the buffer shank at the rear end. Being chambered in their 50 rear portions, they also form housings and seats for the inner springs of the buffer, and also a shoulder against which the prongs of the buffer shank abut.

The draft gear is provided with suitable 55 guiding connections with the truck so as to automatically guide the coupler and buffer to the center of the track, regardless as to whether the car is on a straight track or upon a curve. In the arrangement shown, 60 these guiding connections consist of jaws 24, which depend from the rear portion of the gear case or pocket, and which embrace spring plungers 25 mounted in suitable bearings on the car truck frame.

65 The operation will be readily understood.

The guide connections just described cause the movements of the car truck to move the buffer and coupler to the center of the track. Substantially all buffing stresses are taken up by the springs 10 and 11, the springs 10 70 receiving the first compression as above described, the springs 11 taking the main compression; and after the limit of capacity of these springs has been exhausted, the main buffer casting takes a solid buffer bearing 75 on the buffer segment 3.

By removing the transverse pin 17, the assembled draft rigging may readily be withdrawn from the front of the case or pocket for replacement or repairs. 80

Another feature of my invention consists in the construction of the buffing face of the buffer casting 5, whereby normally a flat buffing surface is presented, but which, in the event of collision, will have an "anti-climbing" action. The ends of a car or car platform have heretofore been provided with ribs or projections of such character that in the event of a collision in which the resulting shock is sufficient to drive back 90 the couplers and draft gears and allow the car ends to come in contact, these ribs or projections and corresponding seats or depressions in the opposing car will come in contact with each other and interlock to 95 prevent the cars climbing or telescoping. My invention contemplates the application

of a similar feature to the buffer casting. The difficulty in such application consists in the fact that the buffing faces of these castings are in direct contact under normal conditions, and it is desirable and necessary that the contacting buffing faces shall be flat and that they shall present no obstruction to either the lateral or vertical movements 100 which must normally occur on account of irregularities in the track or variations in the height of cars. To overcome this difficulty by providing the forward end of the buffing member with anti-climbing ribs or corrugations 5^b, which I normally cover over by a plate member 6. The plate member is suitably secured to the buffing member and has a smooth buffing face. The plate member 6 is of sufficient strength to resist all 105 ordinary shocks and wear incident to its contact with an opposing buffing face. When, however, a collision takes place, the portions of the member 6 which bridge over the depressions between the projections 5^b 110 will be crushed in upon both the opposing buffers. The corrugations of the two buffing members will then interlock and will act in their intended manner. 115

It will be obvious that various changes can 120 be made in the form of the several castings; and in the manner of seating and arranging the buffer springs; that various forms of draft riggings and couplers may be used, together with different guiding connections 125 130

for guiding the coupler and buffer to the center of the track, and that other changes may be made within the scope of the appended claims.

5. What I claim is:—

1. In a draft gear, a rigid buffer segment, a main buffer member slidingly supported by said segment and arranged to have buffing contact therewith, a pivoted draft member, springs interposed between the buffer member and the draft member, and a draft rigging and coupler carried by the draft member, substantially as described.

10. 2. In a draft gear, a rigid buffer segment, a main buffer member having a split or forked shank embracing said segment, a radially swinging draft member, and buffer springs interposed between the main buffer member and the draft member, the draft member having a downwardly offset draft rigging pocket underneath the buffer segment and a draft rigging and coupler, substantially as described.

15. 3. In a draft gear, a car underframe having forwardly diverging center sills and a rigid buffer segment extending transversely between the diverging sills at the forward end portions thereof and taking the place of the end sill, a main buffer member having a forked shank embracing said segment and arranged to have buffing contact therewith, a radially swinging draft member, and a draft rigging and coupler carried by said draft member, substantially as described.

20. 4. In a draft gear, a rigid buffer segment, a main buffer member arranged to have buffing contact with said segment, a radially swinging draft member and buffing springs interposed between the draft member and the main buffing member, the draft member having a downwardly offset draft rigging pocket underneath the buffer segment, said pocket having a support on the main buffer member, substantially as described.

25. 5. In a draft gear, a draft member, and a buffer mounted on the draft member, said buffer having a member provided with depending lateral jaws which support the forward end of the draft member; substantially as described.

30. 6. In a draft gear, a rigid buffer segment, a main buffer member having a sliding support on said segment, and also arranged to have buffing contact therewith, a radially swinging draft member, buffer springs interposed between the main buffer member and the draft member, said draft member

having a draft rigging pocket extending underneath the buffer segment and supported thereby, and a draft rigging and coupler, the support for said rigging and coupler having means for permitting vertical movement of the draft rigging and coupler, substantially as described.

35. 7. In a draft gear, a rigid buffer segment, a main buffer member arranged to have buffing contact with said segment, a radially swinging draft member having a draft rigging pocket extending underneath the buffer segment and supported thereby, and a filler for the main buffer member having means for supporting the draft rigging pocket; substantially as described.

40. 8. In a draft gear, a main buffer casting having a divided shank forming prongs, and a filler for said shank comprising members arranged to be inserted at opposite sides, said filler members having integral supports for a draft member and acting as spacers for the prongs of the buffer shank and also as housings and seats for the buffer springs; substantially as described.

45. 9. In a draft gear, a main buffer member having a divided shank, and a filler for said shank having portions adapted to form a support for a draft rigging case; substantially as described.

50. 10. In a draft gear, a draft member, a buffer, the draft member having its forward portion extending underneath the buffer and provided with means for the attachment of a draft rigging and coupler thereto, the buffer having a member provided with depending lateral jaws and the draft member having supporting members engaging the jaws, substantially as described.

55. 11. A buffing member having its buffing end provided with anti-climbing projections, and a separate buffing member covering said projections and arranged to crush under abnormal shocks, substantially as described.

60. 12. A buffing member having its buffing end provided with anti-climbing projections, and a second buffing member secured to the first named member and having portions bridging the spaces between said projections and of a character to crush under abnormal shock, substantially as described.

In testimony whereof, I have hereunto set my hand.

HARRY T. KRAKAU.
